UNITED STATES PATENT OFFICE

WALLACE H. CAMPBELL, OF AKRON, OHIO, ASSIGNOR TO THE GOODYEAR TIRE & RUBBER COMPANY, OF AKRON, OHIO, A CORPORATION OF OHIO

TUBE-DEFLATING MACHINE

Application filed May 15, 1928. Serial No. 277,955.

This invention relates to machines for deflating expanded articles and it has particular relation to machines of the above designated character which shall be especially applicable for deflating pneumatic tire casing inner tubes which either have been cured in individual molds or upon so-called circular mandrels.

One object of the invention is to provide a tube deflating machine which will be capable of operation in production at a greater rate of speed than the machines of such character heretofore employed.

Another object of the invention is to provide a machine capable of deflating annular rubber tubes having unequal peripheral dimensions without appreciable distortion or wrinkling.

The invention comprises a plurality of tube deflating units which are mounted in spaced relation upon a substantially circular rotatable frame. The units severally are actuated by mechanisms embodying rollers which are associated operatively with a circular camming device mounted concentrically relative to the rotatable deflating unit supporting frame. The deflating units comprise obliquely disposed apertured plates, rigidly secured to the frame of the machine, upon which the bridge plates of inner tubes are supported and through which the valve stems thereof project. Relatively movable clamping jaws, disposed on opposite sides of the support, are adapted clampingly to engage the opposite sidewall portions of the inner tubes at the regions thereof immediately opposite the valve stems. The bridge plates of the inner tubes are secured rigidly to the support by a pair of spaced cams which are rotated intermittently in opposite directions by a mechanism actuated in response to the movement of one of the clamping jaws. When the bridge plates are secured rigidly in position upon the supports, deflating valves, likewise actuated in response to the movement of the clamping jaws, are moved positively into engagement with the ends of the inner tube valve stems projecting through the supporting plates. The remaining portions of the inner tubes suspended from the

clamping jaws, are supported by pairs of spaced members secured rigidly to the frame, which members engage the inner tubes only along the sidewall portion thereof, thus insuring the collapse of the inner tubes along their median planes.

For a better understanding of the invention, reference may now be had to the accompanying drawings, forming a part of the specification, of which:

Fig. 1 is a fragmentary cross-sectional view of a tube deflating machine constructed according to the invention and embodying a side elevational view of one of the tube deflating units thereof;

Fig. 2 is a fragmentary view, similar to that illustrated by Fig. 1, in which the elements of the mechanism are shown in different relative positions;

Fig. 3 is a fragmentary view of the deflating machine taken from the outer end of one of the deflating units and including a fragmentary cross-sectional view of the latter taken substantially on line III-III of Fig. 1;

Fig. 4 is a fragmentary cross-sectional view, on a larger scale, taken substantially on line IV-IV of Fig. 1 and illustrating a portion of an inner tube associated operatively with the deflating machine; and

Fig. 5 is a fragmentary cross-sectional view of one of the deflating units taken substantially on line V-V of Fig. 1.

In the illustrated embodiment of the invention, a circular fabricated frame 10 is rotatably mounted at its center upon a vertically disposed shaft, not shown. The frame comprises a plurality of spaced pairs of radially disposed elongate members 11 which are connected together at their outer ends by annular angle members 12 and 15 secured rigidly at intervals thereto. The outer ends of the pairs of members 11 and the angle members 12 and 15 are secured rigidly together at intervals by vertically disposed bars 20. An annular frame 13, disposed concentrically with respect to the frame 10, supports spaced cam plates 14 and 16, a greater portion of which are spaced uniformly below the frame 10, thus providing a lower

cam surface portion 17. At the opposite ends of the aforesaid cam surface portion (Fig. 3) the plates 14 and 16 are deflected toward the frame 10 in order to provide inclined cam surface portions 18. At the opposite ends of these portions, the plates 14 and 16 again project in a direction parallel to the cam surface 17, thus providing a cam surface 19 which likewise is uniformly spaced below the frame 10.

A plurality of tube deflating units 21, projecting radially at spaced intervals from the outer periphery of the frame 10, are actuated by a plurality of rollers 24 disposed operatively between the plates 14 and 16 and rotatably mounted on pins 26 rigidly secured in bosses 27 formed at the lower ends of vertically disposed bars 28. Upper portions of the bars 28 are slidably disposed in openings formed in brackets 29 which are rigidly secured to the frame 10. Obliquely disposed arms 31 bolted at one end, as indicated at 32, to the upper end of the bars 28, are provided with spaced lugs 33 at the opposite ends thereof in which cap-screw trunnions 34 are operatively journaled. The trunnions project laterally from blocks 36 embodying vertically disposed sleeves 37, which are slidably mounted on elongate rods 38. Blocks 39, rigidly secured by nuts 41 on the lower end of the rods 38, pivotally support handles 42 provided with spaced lugs 43 at the lower ends thereof, which are journaled upon trunnions 44 projecting laterally from the blocks. Springs 46, secured between the blocks 39 and the handles 42 resiliently tend to maintain the latter in a vertical position. The upper ends of the handles 42 are provided with spaced pairs of lugs 47 which encircle portions of the rods 38 and upon which the lower ends of the trunnion sleeves 37 are adapted to be supported. Thus when the rollers 24 are urged downwardly by one of the inclined cam surfaces 18, the rods 38 likewise are carried downwardly by reason of the engagement between the lower ends of the sleeves 37 and the lugs 47.

During the operation of the machine, if any element of the mechanism of one of the tube deflating units should become broken or if for any other reason it should become desirable to discontinue the employment of any unit of the machine, that unit may be rendered inoperative by manually grasping the handle 42 and so pivoting it outwardly upon the trunnions 44 as to disengage the lugs 47 from the lower end of the sleeve 37, thus permitting the latter to reciprocate idly upon the rod 38. In order to prevent the lugs 47 from becoming engaged above the trunnion block 36, a bar 35 is secured rigidly upon one of the cap screw trunnions 34 and projects vertically upward in parallel relation to the rod 38. Thus when the lugs 47 are inoper-

atively disposed with respect to the rod 38, the ends thereof slidably engage the bar 35.

The upper ends of the rods 38 are secured rigidly upon pins 48 which are rotatably mounted in the bifurcated ends 49 of levers 51. Weights 45, mounted adjustably on rods 50, which, in turn, are secured rigidly to the ends of the levers 51 and project laterally therebeyond, tend continuously to urge the aforesaid end of the levers downwardly. Springs 52, confined between the bifurcated ends 49 of the levers 51 and the upper ends of the sleeves 37 resiliently urge the ends of the levers 51 upwardly when the rollers 24 ascend one of the inclined cam surfaces 18. The levers 51 are intermediately pivoted upon pins 53, which are rigidly secured between spaced pairs of vertically disposed plates 54. The inner ends of the plates 54 are secured to upper and outer portions of the frame 10.

The ends of the levers 51 beyond the pins 53 are provided with transversely disposed arms 55 to which clamping jaws 56, composed of rubber or other suitable material, are secured adjacent the ends thereof. Pins 57, rigidly secured in the levers 51 adjacent the arms 55, pivotally support ends of links 58 that likewise are pivotally supported at their opposite ends upon pins 59 secured rigidly between pairs of lugs 61 projecting normally from the upper surfaces of bifurcated levers 62. The ends of the latter opposite the lugs 61 are pivotally mounted upon pins 63 secured rigidly between outer end portions of the plates 54. The ends of the bifurcated levers 62, opposite the pins 63 and immediately adjacent the lugs 61, are projected laterally and parallel to the arms 55 in order to provide arms 64. Clamping jaws 66, similar to the jaws 56 and disposed oppositely thereto, are secured rigidly to the arms 64 adjacent the ends thereof.

Pins 68 are journaled at opposite ends in aligned openings formed in the levers 51 and in the ends of bosses 67 disposed in parallel relation to the latter and formed integrally therewith. Openings formed transversely within the pins 68 are adapted slidably to receive intermediate portions of rods 69 having springs 71 mounted thereon and confined between washers 72 disposed against the pins 68, and lock nuts 73 engaging the threaded ends thereof. The opposite ends of the rods 69 are provided with flattened portions 74, which are pivotally secured on pins 76 that are disposed between the slotted ends of obliquely disposed rods 77. Spaced bars 78, secured at their opposite ends between plates 54, by bolts 81, are provided with aligned openings disposed intermediate the ends thereof in which the rods 77 are slidably mounted. Between the bars 78, the rods 77 are provided with arcuately formed grooves 82 at the opposite sides of which collars 83 are rigidly secured upon the rods.

Diametrically opposed surfaces of the grooved portions 82 of the rods 77 are adapted to be engaged slidably by the ends of inwardly disposed pairs of fingers 84 projecting from corresponding ends of a pair of spaced rods 86. Adjacent the fingers 84, the rods 86 are journaled in spaced openings formed transversely in a block 87 that is bolted at opposite ends, as indicated at 88, between the plates 54. 5 Beyond the block 87, the rods 86 project transversely toward the arms 55 and 64 and are spaced equally therefrom adjacent the inner ends of the clamping jaws 56 and 66. The ends of the rods 86 are journaled in angle 10 brackets 89 which are secured rigidly beneath a support or bar 91, the latter being uniformly disposed in spaced relation to the rods 86 on the sides thereof opposite the clamping jaws 56 and 66. Immediately above the 15 support 91, the rods 86 are provided with oppositely disposed integral cams 92. Aper- 20 tures formed in the intermediate portions of the plate 91 and equally spaced between the cams 92, are adapted to receive relatively short 25 sleeves 95 which project slightly below the lower surfaces thereof.

The opposite ends of the supports 91 are mounted upon the upper ends of spaced pairs of guides 93, which, in turn, are secured 30 rigidly adjacent their lower ends between the plates 54. Yokes 96, slidably mounted at opposite ends upon the guides 93, are pro- 35 vided with intermediately disposed apertures for receiving end portions of deflating valves 97 which are connected to a common vacuum pump (not shown) by conduits 98. Spaced rods 99, secured at their upper ends in open- 40 ings projecting transversely through the yokes 96, are adapted slidably to engage open- 45 ings formed in the ends of the pins 59 pro- 50 jecting beyond the bifurcated portions of the arms 62. Cotter pins 101, secured below the pins 59 in the ends of the rods 99 limit the movement of the latter in one direction. 55 Springs 102, surrounding the rods 99 and abutting the yokes 96 and the pins 59 at op- 60 posite ends thereof, resiliently urge the deflating valves 97 toward the supports 91.

The upper ends of pairs of substantially 65 vertically disposed rods 103 are secured rigidly in spaced relation upon the pins 63 which support the ends of the levers 62. The lower ends of the rods are bent inwardly to- 70 ward the frame 10 of the tube deflating ma- 75 chine and are secured rigidly in spaced open- 80 ings formed in the brackets 29.

In the operation of the embodiment of the invention described in detail hereinbefore, the frame 10, carrying a plurality of the tube 85 deflating units 21, is rotated continuously by a motor (not shown). The rollers 24, while traversing the cam surface 19, elevate the ends of the levers 51 engaged by the rods 38 and thus maintain the clamping jaws 56 90 and 66 in spaced relation (as shown in Fig. 65

2) on opposite sides of the support 91. Also the deflating valves 97 are moved downwardly away from the supports 91 and the cams 92 are so rotated by movement of the grooved portions 82 of the rod 77 as likewise to be 70 disposed remotely from the plate. While the elements of the mechanism of a number of the deflating units are disposed in this re- 75 lation, an attendant successively inserts valve stems 104 of inner tubes 106 within the sleeve 95 of the units and positions the inclined ends of bridge plates 107 of the tube beneath and between the cams 92 thereof.

Subsequently when the rollers 24 of the 80 units successively traverse one of the cam surfaces 18, the resulting movement of the 85 ends of the levers 51 engaging the rods 38, closes the clamping jaws 56 and 66 upon por- 90 tions of the inner tubes immediately above the valve stems thereof; moves the deflating 95 valves 97 into operative engagement with the outer ends of the aforesaid valve stems; and so rotates the cams 92 as to urge the 100 bridge plates 107 into engagement with the supports 91. Later, during the movement of 105 the rollers 24 upon the lower cam surface 17, the fluid within the inner tubes 106 is ex- 110 hausted through the deflating valves 97. Since only one sidewall portion of each inner tube is supported by the spaced rods 103, the tubes are collapsed uniformly along the median planes thereof. When the rollers 24 115 traverse the upwardly inclined cam surfaces 18, the inner tubes 106 are released by the clamping jaws 56 and 66 and the remaining 120 elements of the mechanism assume their nor- 125 mal position as hereinbefore described. The deflated tubes 106 are removed successively from the supports 91 while the aforesaid cycle of operation is continued.

From the foregoing description, it is 130 apparent that the invention provides a very simple and inexpensive machine for uniformly collapsing inner tubes along their median planes in order to facilitate their convenient packing and handling. Spliced inner tubes, in which there is a very great tendency toward wrinkling, are easily de- 135 flated by the aforesaid apparatus by reason of the spaced rods which may be made to support one sidewall portion of an inner tube on opposite sides of the splice therein. The operation rate of this machine in produc- 140 tion is substantially greater than that of the machines ordinarily employed, by reason of the fact that the tubes are held in such position that the fluid therefrom exhausts very rapidly, and furthermore because little time is required in applying and removing the tubes from the machine.

Although I have illustrated only the preferred form which the invention may assume and have described that form in detail, it will be apparent to those skilled in the art that the invention is not so limited but that 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 9900 9905 991

various modifications may be made therein without departing from the spirit of the invention or from the scope of the appended claims.

5. What I claim is:

1. A tube deflating machine comprising a rigid support for a bridge plate of an inner tube, means for securing the plate against the support, and means for moving a deflating valve into operative relation to a valve stem of the tube.

10. 2. A tube deflating machine comprising a support for a bridge plate of an inner tube, means for securing the plate against the support, a pair of relatively movable jaws for engaging opposite sidewall portions of the tube, a deflating valve, and means controlled by the position of the jaws for moving the deflating valve relative to a valve stem of the tube.

15. 3. A tube deflating machine comprising a support for a bridge plate of an inner tube, a pair of spaced cams adjacent the plate, and means for rotating the cams against the plate for securing the latter to the support.

20. 4. A tube deflating machine comprising a support for a bridge plate of an inner tube, a pair of spaced cams adjacent the plate, a pair of relatively movable jaws for engaging opposite sidewall portions of the tube, and means controlled by the position of the jaws for rotating the cams against the plate for securing the latter to the support.

25. 5. A tube deflating machine comprising a support for a bridge plate of an inner tube, a deflating valve associated movably therewith, and a pair of spaced supporting members for engaging one sidewall portion of the tube.

30. 6. A tube deflating machine comprising a support for a bridge plate of an inner tube, a deflating valve associated therewith, a pair of relatively movable jaws for engaging opposite sidewall portions of the tube in the region adjacent the valve stem thereof, and means remote therefrom for supporting a single sidewall portion of the tube.

35. 7. A tube deflating machine comprising a support for a bridge plate of an inner tube, a pair of guides projecting below the support, a deflating valve slidably mounted upon the guides, a pair of relatively movable jaws for engaging opposite sidewall portions of the tube and means controlled by the position of the jaws for moving the deflating valve relative to a valve stem of the tube.

40. 8. A tube deflating machine comprising a support for a bridge plate of an inner tube, a spaced pair of rotatable cams adjacent the support for engaging the bridge plate, a pair of relatively movable jaws for engaging opposite sidewall portions of the tube, means controlled by the position of the jaws for rotating the cams and a resilient element operatively associated with the means.

In witness whereof, I have hereunto signed my name.

Signed at Akron, in the county of Summit, and State of Ohio, this 12th day of May, 1928.

WALLACE H. CAMPBELL.
